EXPANSION AND TENSIONING DEVICE FOR ALUMINUM ALLOY PISTONS

George J. Moeller, Maplewood, Mo., assignor to
Ramsey Accessories Manufacturing Corpora-
tion, St. Louis, Mo., a corporation of Missouri

Substitute for abandoned application Serial No.
691,612, September 30, 1933. This applica-
tion January 26, 1934, Serial No. 708,361

1 Claim. (Cl. 309—12)

My invention has relation to improvements in
expansion and tensioning devices for aluminum
alloy pistons and it consists in the novel features
of construction more fully set forth in the speci-
fication and pointed out in the claims. The
present application is a substitute for that here-
tofore filed September 30, 1933, on the same sub-
ject-matter by Charles A. Marien and myself
under Serial No. 691,612.

10 It is a matter of common knowledge in the
automotive industry that alloy pistons must be
longitudinally slotted in order to allow for the
unequal degree of expansion between the pistons
and the cast iron cylinders. This slot introduces
15 an element of weakness in the piston structure
ultimately causing the piston to collapse in the
lower part of the skirt and introducing a piston
slap in operation. It has heretofore been pro-
posed to correct this condition by placing steel
20 expanding rings in the lower part of the skirt
to restore the piston to its proper shape and
reenforce the skirt so that it will again ride
squarely on the cylinder wall and possess the
proper degree of resiliency so that it will yield
25 to excessive pressures placed upon it due to in-
equalities in the expansion of said cylinder wall.
In the patent of Harold F. Phillips, Reissue No.
18,653, dated November 15, 1932, the principle of
expanding a piston skirt in a direction at right
30 angles to the pin bosses is disclosed, and in the
patent of Charles A. Marien, No. 1,887,769, dated
November 15, 1932, a particular type of expand-
ing ring is shown wherein the expanding ring
is so shaped that pressure at right angles to the
35 pin bosses is assured.

However, in both of these patents the construc-
tion of the piston is relied on to secure the ex-
pander in place. Some pistons are so construct-
ed as not to present appropriate recesses, or other
40 formations for holding the expander ring in place,
in which event the expander itself must be pro-
vided with the elements for securing it in place.

It is the object of the present invention to
45 provide a skirt expander that may be anchored
either on the piston pin or the piston pin bosses,
said expander having skirt expanding parts pro-
jecting downwardly from the point of anchorage
to be effective on the lower part of the skirt by
50 exerting tension thereon at right angles to the
axis of the pin bosses. The present invention
contemplates two forms of such elements, one of
which may be made of spring wire bent into the
proper shape to perform its function, and the
55 other comprising a stamping of spring steel sub-

serving the same function in the same way as
the wire expander.

A further object of the invention is to provide
an expander that may be effectively secured in
the piston and which is durable and long-lived, 5
although it may be cheaply manufactured. Other
advantages inherent in the invention will be
better apparent from a detailed description of
the same in connection with the accompanying
drawing, in which:

Figure 1 is a side elevation of a longitudinally
slotted piston with part of the wall broken away
to show my improved skirt expander securely
fixed within the skirt; Fig. 2 is a bottom plan of
15 the piston showing the skirt expander lodged
therein; Fig. 3 is a vertical longitudinal section
taken on the line 3—3 of Fig. 1; Fig. 4 is a per-
spective view of the expander (shown in Figs. 1
to 3, inclusive) removed from the piston skirt
20 and, of course, not under tension; Figs. 5, 6 and 20
7 are views corresponding to Figs. 1, 2 and 3, re-
spectively, showing a modified form of expander
produced from sheet metal instead of wire; and
Fig. 8 is a development of the modified form of
25 expander showing the shape of the stamping
before the same is formed so as to perform its
spring function.

Referring to the drawing, P represents a pis-
ton provided with the usual pin bosses 1, 1 in
which the piston pin 2 is lodged and having a 30
longitudinally disposed slot 3 in the piston skirt
4, according to the practice now common in the
art. E represents my improved expander bent
from a suitable length of spring wire 5 so as to
have oppositely disposed U-shaped spring arms 35
or wings 6, 6 connected by axially aligned coils
7, 7 centrally disposed with respect to the arms
6, 6, said coils serving as the hinge point for the
arms 6, 6. The wire 5 is preferably bent so that
40 the ends will come together at the end of one
of the arms 6, as shown at 8, and they are then
effectively secured together by welding, or braz-
ing, or soldering. The coils or lobes 7, 7 are of
sufficient diameter so that they will receive the
piston pin bosses 1, 1, as shown in Figs. 1 to 3, 45
inclusive. The U-shaped spring arms 6, 6 when
not under tension make a considerably greater
angle with each other than when they are under
tension by confinement within the skirt 4 of the
piston, although the tension may be regulated 50
by varying this angle so that the correct amount
of tension may be obtained to give most satis-
factory results on pistons of different design.
The cross elements 6', 6' at the ends of the spring
arms 6, 6 are preferably arcuate so that they will 55

fit snugly within the piston skirt and contact therewith throughout their entire length (as shown in Fig. 2).

In the modification shown in Figs. 5 to 8, inclusive, the expander E' is formed from a stamping 10, said stamping having oppositely disposed wings 11, 11 embossed, as shown at 12, for increasing their strength, and oppositely disposed lobes 13, 13 at right angles to the wings 11, 11, said lobes each having an opening 14 to receive the piston pin 2 when the expander is inserted within the piston. The stamping 10 is given its proper shape by bending the lobes 13, 13 along the dotted lines x, x shown on the connecting necks 15, 15 between the wings 11, 11 and lobes 13, 13. The lobes are bent at right angles to the wing portions 11, 11 of the stamping, after which the wing portions themselves are bent to substantially the shape shown by the dotted positions of the wings 11, 11 in Fig. 7. The ends of the wings are formed with arcuate extremities 16, 16 for making contact with the bottom of the piston skirt, as shown in Figs. 5 to 7, inclusive. After the expander E' has been bent to its proper shape it is, of course, properly tem-

pered so that the wings 11, 11, which perform the functions of spring arms when the expander is in the skirt, will have the proper tension to maintain the piston skirt properly expanded and offer the right amount of resistance to the thrusts that are encountered as the piston operates in the engine cylinder.

While the invention is primarily adapted for use with aluminum alloy pistons, most of which have a longitudinally slotted skirt, as above pointed out, it is also useful in cast iron pistons, especially if they have comparatively thin walls, and pistons of other types. I do not, therefore, wish to be restricted to a tensioning device for use either in slotted skirt pistons or aluminum alloy pistons whether the skirt is slotted or not.

Having described my invention, I claim:

In combination with a piston assembly, an expander in the piston skirt comprising a wire bent to form oppositely disposed U-shaped spring arms adapted to bear against the piston skirt, corresponding sides of the U-shaped spring arms being connected by loops for securing the expander in the piston assembly.

GEORGE J. MOELLER. 25
